[57] CLAIM

The ornamental design for pre-measured dispensing ampule, as shown and described.

DESCRIPTION

FIG. 1 is a front elevational view of a pre-measured dispensing ampule showing my new design, the undisclosed opposite side being identical;

FIG. 2 is a top plan view thereof;

FIG. 3 is a left side elevational view thereof;

FIG. 4 is a bottom plan view thereof; and,

FIG. 5 is a right side elevational view thereof.
